UNITED STATES PATENT OFFICE.

JOSEPH A. FIRSCHING, OF UTICA, NEW YORK.

CLOTH-MARKING MACHINE.

1,072,708.

Specification of Letters Patent.

Patented Sept. 9, 1913.

Application filed December 18, 1909. Serial No. 533,944.

To all whom it may concern:

Be it known that I, JOSEPH A. FIRSCHING, a citizen of the United States, residing in Utica, in the county of Oneida and State of New York, have invented certain new and useful Improvements in Cloth-Marking Machines, of which the following is a specification.

In the manufacture of underwear, and more particularly of undervests, there is a step which results in the formation of the neck portion of the garment. In the more generally used class of goods, these garments are formed from what is known in the art as "tubular-knit" fabric. Portions of the fabric are cut out into approximately proper lengths; the neck portion, which is substantially semi-circular, is marked; is sewn to what would be the back of the garment, and is then cut, and the neck portion is suitably bound with an edging. It has heretofore been the custom in connection with this step in the art, to mark out the pattern with a pencil. It happens that in finishing the garment, the edging hereinbefore referred to, failed to conceal this pencil mark, and, as a result, objection was raised when the goods were placed on sale. Later in the art, it was conceived to mark the portion to be cut, by impressing a ridge in the goods with a cold die. It happens, however, that these goods are not always immediately worked up in the finished article, and, as a result, the cold die impression would vanish, before the cutting process would take place, and the marking would either have to be repeated, or else the neck portion cut out with some degree of guess work. Another disadvantageous feature in the prior art with relation to this step in the manufacture of garments of this kind, consisted in the apparent inability to register the mark or the impression at the proper place; therefore, in the finished garment, it would be discovered that the neck portion thereof was not properly located, in consequence whereof, the garment would be unfit for wear, or else would have to be sold, as a second, at a considerably reduced rate.

In observance of these and other manifest deficiencies, this invention has been directed to the proper locating of a mark or impression on a garment, and to prolong the life of that impression.

In order to accomplish these, and other apparent objects, mechanism has been con-

structed, an illustration of which may be found on the sheet of drawings that accompany, and form a part of this specification; it being understood, of course, that although the invention is illustrated as so clothed in such mechanism, it does not follow that such mechanism constitutes the only essential elements.

In these drawings: Figure 1 illustrates the mechanism in front elevation showing a marker, means for positioning the goods with relation thereto, and means for heating marker-dies before and after use; Fig. 2 illustrates an end view in elevation of the same structure, whereby some details of the structure at the rear of the machine may be more easily observed; Fig. 3 illustrates a top plan view of the machine; Fig. 4 illustrates in elevation, and disassembled from the machine proper, a fabric positioning mechanism; Fig. 5 is an end view in elevation thereof; Fig. 6 illustrates a top plan view incorporating the positioning scheme; Figs. 7 and 8 illustrate certain details of structure in connection with the positioning device; Fig. 9 illustrates one form of a marker-die heating head; Fig. 10 illustrates another form; perhaps the most practical one; Fig. 11 incorporates three views of a marking die; Fig. 12 illustrates, in elevation, also in section, partially, the construction of a suitable form of tripping mechanism and operating mechanism for vertically reciprocating, at will, the marker head with relation to the machine cloth table; Fig. 13 is a view similar to that illustrated in Fig. 12, except that it is more fragmentary, and shows a reversed position of the parts; Fig. 14 is a sectional view taken on line A and B of Fig. 12; Fig. 15 illustrates in elevation the same parts illustrated in Figs. 12 and 13; Fig. 16 embodies two views showing the position of a cam operated mechanism, the position of the various parts of which has been induced by the position of the parts illustrated in Fig. 12, and Fig. 17 embodies two views of the position of the parts of the cam-operating mechanism, while the parts are in the position shown in Fig. 15.

Similar characters of reference indicate similar parts throughout the figures.

By reference more particularly to Figs. 1 and 2 it will be noted, that for convenience, a table 23 is supported by a base 24 and an intermediately disposed standard 25. Suitably journaled, as at 26, in the standard 25,

and as at 29, in an arm 28, at the rear of the standard 25 and base 24, is a shaft 27, upon which is mounted for normal idle rotation, a fly wheel 30. At the rear of the standard 25, in the present instance, are guides 31, in which is mounted for reciprocation a slide 32, to which is connected a head 33. Near the lower portion of this slide 32 is a laterally extended lug 34 through which is passed a rod 35, connected to a member in the form of a yoke 36, mounted for vertical reciprocation in guides 37, formed with or upon the standard 25. This yoke may be suitably formed in the manner as shown in Figs. 16 and 17, and incloses the shaft 27. Mounted on this shaft 27, and affixed thereto is a compound cam 38, one face, as 39, of which is adapted to operate in conjunction with a portion 40 of the yoke 36, while the opposite side of the cam, and its face, as 41, will operate in conjunction with another portion 42 of said yoke. In fuller explanation of this feature of the case, it might be stated, that, by reference to Fig. 17, the dotted-in portion of the cam operates in conjunction with the dotted-in portion of the yoke; and the full line portion of the cam operates in conjunction with the full line portion of the yoke.

Keyed or otherwise secured to shaft 27 is a bushing or elongated collar 43, and this is also affixed to the shaft. Slidably mounted on said shaft 27 is a collar 44, which, at times, occupies a recess 45 in the collar 43. Collar 44 is provided with a cam face 46, the purpose of which will be hereinafter mentioned. Collar 44 controls the movement of a pin 47, which is actuated forward by a spiral spring 48, seated in a recess 49 in the collar 43. Pivoted as at 50, to a lug 51, carried by the standard 28, is a treadle-bar 52, whose tread-portion 53 protrudes forward through an opening 54 in the base portion 24. Suitably connected to bar 52 is a stem 55 which is normally sustained in an elevated position by a spring 56 operating against a pin 57 in the bar 55, thus, as will be observed, by reference to Fig. 12, the end 58 of bar 55 is normally positioned against the cam-face 46 of the ring or collar, whereby the pin 47 is abnormally disengaged from the fixed pin 59; carried in the hub 60 of the fly wheel 30.

As may be noted, pressure on the treadle 53 will cause the end 58 of the bar 55 to disengage the cam-collar 44. At that time, an outward movement of the latter, under pressure of spring 48, will bring the pin 47, carried by the collar 44 into the path of the pin 59, carried by the hub 60 of the fly wheel 30. At the engagement of these two pins 47 and 59 respectively, the collar 43, the shaft 27 and the cam will operate in coincidence with the fly wheel 30. In turn, the

yoke 36 will reciprocate in its slide 37, also causing the head 33 through the connection 35 to operate.

The position assumed by cam 38 in Fig. 17 indicates that the marker head is in an operative position, that is, cam 38 will cause the marker carried by the marker head to make its impression on the underlying cloth. The construction of the cam and the yoke is such as to cause the marker head to pause for a given period while in an operative position, whereby to effectually create a lasting impression on the goods. The position of cam 38 in Fig. 16 will indicate a reverse of the position just mentioned.

In the varying positions of the compound cam a spiral spring 61 becomes effective for automatically actuating the yoke 36 and for returning the head 33 to a normal or inoperative position.

It will be noticed now that the movement of the compound cam is urged continually in one direction, through the instrumentality of the pin 59 on the hub 60 of the wheel 30 operating against the pin 47, carried by the collar 43; therefore, in order to prevent a re-action in a reverse direction of the movement of the cam, one of its portions is provided with a notch 62, into which a spring actuated bolt 63 drops automatically when one portion of the cam passes a trifle beyond a vertical line or position of the cam as shown in Fig. 16.

It is to be understood, of course, that as soon as the mechanism is in operation the treadle is released. This automatically returns the bar 55 to its normal position. When the end 58 of bar 55 is in a position to co-operate with the cam face 46 of the collar 44, it will in turn cause the latter to recede to an abnormal position whereupon the two pins 47 and 49 will become disassociated.

To the head 33 is suspended a heater 64 which may be of any form, as that illustrated in Figs. 9 or 10. In the former figure the heater consists of a body having a cylindrical bore 65 into which is deposited an elongated cylindrical electrical heating unit 66. In Fig. 10 a flat heating unit is sandwiched between the upper and lower portions 68 and 69 for the same purpose.

Tongues 72 of markers 73 engage guides 70 and 71 secured to the under side of heater 64, it being understood that there may be a plurality of markers. A detent 75 is provided for holding markers 73 in place on guides 70 and 71, while in use. Mechanism is also provided for establishing a positive contact between the heater and the marker. This may be done by simply forming spring-lips 109 and 110 on the guides 70 and 71.

It will now be seen that I have provided, through the instrumentality of a simple form of mechanism, practical in detail,

means for mechanically and electrically pressing upon fabric a pattern, and that to effectually form the impression, the contact between the heated dies and the goods is substantially prolonged.

5 In order to so position the fabric that the marker hereinafter referred to will create its impression at the proper place on the goods, there is formed on or with the standard 25, two wings 76 and 77, to which are connected by pivots 78 and 79, bell crank levers or arms 80 and 81. The ends 82 and 83 of these members 80 and 81 are provided with segment-racks 84 and 85, so meshing as to simultaneously affect the operation of each arm 86 and 87 of the bell cranks when either is operated, so that their upper free ends 88 and 89 respectively will move in unison and in coincidence with a given central point.

20 Slidably mounted in an eye or yoke 90 in each arm end, is a block 91 held thereto by set-screws 92, and this block is provided with a projecting cloth pin 93 over which to slide the fabric 94, as seen, for instance, in Fig. 6. These blocks are recessed, as at 95, to accommodate a guide rod 96 which is formed by standards 97 and 98 on a table 23, and these blocks are held to the rod 96 by 25 plates 99 secured to the blocks by set-screws 100. Extending from one of the arms is a finger 101 through which is passed a pin 102 having a handle 103 and governed by a spring 104, (see Fig. 7). A gage 105 is provided with openings 106 into any of which, at will, the end of the pin 102 may take when setting the arms of the cloth positioning device to accommodate widths of 30 different size. The gage 105 is mounted on 35 supports 107 and 108.

40 It will be understood, of course, that the markers heretofore referred to may be of different sizes and of different design, and it may be desirable to shift from one style of 45 work to another.

45 It will now be seen that a simple, inexpensive and practical machine has been constructed whereby, through the instrumentality of a heated die, a substantial, permanent impression may be created on fabric for the purpose specified; that means have been provided whereby this impression may be placed correctly, as to position, upon the goods.

55 Having thus described this invention, I claim:

1. In a cloth marking machine, the combination of a reciprocating head, a slidably mounted member, a connection between said head and member, a yoke carried by said member, a cam revoluble in said yoke, guides for said yoke, a shaft for mounting said cam, a collar slidably mounted on said shaft, a connection carried by said collar, a 60 driving wheel revolving on said shaft,

means for operating the cam at will, and a plunger for preventing said cam from rotating in one direction.

2. In a device of the character described, the combination of a vertically reciprocating head, a slidably mounted spring actuated yoke, a connection between said head and yoke, a cam operable within said yoke, said cam adapted to intermittently contact with said yoke, a shaft for mounting said cam, a collar slidably mounted on said shaft, a connection carried by said collar, a driving wheel revoluble on said shaft, means to revolve said cam at will, and a plunger for preventing said cam from rotating in 70 one direction.

3. In a cloth marking device of the character described, the combination of a vertically reciprocating marker-head, a slidably mounted spring actuated yoke, a connection between said head and said yoke, a cam revoluble within said yoke, said cam adapted to intermittently contact with said yoke, a shaft for mounting said cam, a collar slidably mounted on said shaft, a driving wheel revolving on said shaft, means 75 to revolving said cam at will, and a plunger for preventing said cam from rotating in one direction.

4. In a cloth marking machine, the combination of a vertically reciprocated marker-head, a marker carried thereby, a shaft, a fly wheel loosely mounted on said shaft, a yoke mounted for vertical reciprocation, said yoke having a portion adapted to engage with a cam, differently formed faces on said cam, whereby to reciprocate said yoke, a plunger for preventing said cam from rotating in one direction, and means for forming an operative connection between said cam and 80 said fly wheel.

5. In a cloth marking machine, the combination of a vertically movable slide, a marker-head having a heater carried by said slide, a shaft, a fly wheel mounted on said shaft, a yoke mounted for vertical reciprocating movement, a compound cam operating within said yoke, said cam adapted to reciprocate said yoke, means for turning said cam continually in one direction, and means associated with said cam for forming an operative connection between said cam and said fly wheel.

6. In a cloth marker, the combination of a marker-head, a marker carried thereby, a vertically sliding yoke, a spring for urging said yoke to a normal position, a shaft, a fly wheel rotatable on said shaft, a compound cam secured to said shaft, a portion of said cam adapted to actuate said yoke, and means for compelling said cam to turn with said fly wheel, whereby to reciprocate said yoke, said means comprising a pin rigidly secured to the hub of said fly wheel, 120 a second pin carried by said slidably mounted 125 second pin carried by said slidably mounted 130

collar on said shaft, a spring for urging said second pin carried by said elastically mounted collar into engagement with said first mentioned pin, and a cam surface on said slidingly mounted collar, adapted to be engaged by the end of a bar, whereby to disengage said pins to elevate the head.

7. In a cloth marking machine of the character described, the combination of a standard supporting a vertically movable marker-head, a marker carried thereby, a vertically sliding yoke having a portion for temporary association with a compound cam, said cam mounted upon a shaft, a fly wheel mounted upon said shaft, means for connecting said fly wheel with said cam, said means comprising a pin secured to the hub of said fly wheel, a second pin secured to a collar slidingly mounted on said shaft, a spring for normally holding said second pin in contact with said first named pin and cam means for dissociating said pins.

8. In a cloth marking machine, the combination of a pair of pivoted levers, means for causing said levers to operate in unison at will, means for sustaining said levers equal distances on each side of a central point, means carried by said levers for controlling a fabric, a gage, a finger for determining the position of said levers with reference to said gage, and means for guiding the free ends of said levers.

9. In a cloth marking machine, the combination of a pair of bell crank levers, seg-

ment racks formed upon said bell crank levers, means for causing said levers to operate in unison at will, means for disposing said levers equal distances on each side of a given point, means carried by said levers for controlling a fabric, a gage for determining the position of said levers, and means for guiding the free ends of said levers.

10. In a device of the character described, the combination of a pair of pivoted arms, racks carried by each arm for causing said arms to operate in unison, at will, pins carried by said arms for controlling a fabric, a finger for determining the position of said arms, and means for guiding said finger.

11. In a device of the character described, the combination of a pair of rocking arms, connections for causing said arms to operate in unison and at will, blocks carried by said arms, pins carried by said blocks for controlling the fabric and for placing it equally on each side of a central point, a gage, a finger for determining the position of said arms with respect to said gage, and a rod for guiding the free ends of said arms.

In witness whereof, I have hereunto set my hand this tenth day of December, 1909, at Utica, Oneida county, New York.

JOSEPH A. FIRSCHING.
